[57] **CLAIM**

The ornamental design for a shower and tub caddy, as shown and described.

DESCRIPTION

FIG. 1 is a top, front, and right side perspective view of a shower and tub caddy showing my new design, the broken-line depiction of suction cups for wall-mounting being for illustrative purposes only and forming no part of the claimed design;

FIG. 2 is a top plan view thereof;

FIG. 3 is a front elevational view thereof;

FIG. 4 is a left side elevational view thereof;

FIG. 5 is a rear elevational view thereof; and

FIG. 6 is a bottom plan view thereof.

FIG. 1

FIG. 2

FIG.3

FIG.4

FIG.4A

FIG.5

FIG. 6
